(57) **CLAIM**

The ornamental design for a toy cake as shown and described.

DESCRIPTION

FIG. 1 is a front, top, right side perspective view of a toy cake showing my new design;

FIG. 2 is a rear, top, left side perspective view thereof;

FIG. 3 is a front view thereof;

FIG. 4 is a rear view thereof;

FIG. 5 is a top view thereof;

FIG. 6 is a right side view thereof; and,

FIG. 7 is a left side view thereof.

The broken lines in the drawings are for the purpose of illustrating portions of the toy cake that form no part of the claimed design.

The dash-dot broken line defines the bounds of the claimed design and forms no part thereof.

1 Claim, 7 Drawing Sheets
